UNITED STATES PATENT OFFICE.

JAMES BOLTON, OF CHICAGO, ILLINOIS.

FEEDING MECHANISM FOR SEWING-MACHINES.

SPECIFICATION forming part of Letters Patent No. 484,402, dated October 18, 1892.

Application filed March 3, 1892. Serial No. 423,643. (No model.)

To all whom it may concern:

Be it known that I, JAMES BOLTON, a citizen of the United States, residing at Chicago, in the county of Cook and State of Illinois, have 5 invented certain new and useful Improvements in Sewing-Machine Feeding Mechanisms, of which the following is a specification, reference being had therein to the accompanying drawings.

10 My invention has for its object to provide an improved sewing-machine feeding mechanism in which the main rotating shaft is journaled in the upper part of the arm of the machine and is provided with a crank or eccentric the movements of which are transmitted to the mechanism beneath the work-plate by a pitman-lever.

In carrying my invention into effect the 15 vibrating movements of the pitman-lever are utilized for imparting motion to a rock-shaft, from which the longitudinal or feeding movements are given to the feed-bar and a feed-dog carried thereby. The lifting movements of the feed-bar and feed-dog are derived from a 20 suitable cam on a second shaft, which receives its movements from the pitman-lever.

In the accompanying drawings, Figure 1 is a side view, partly in section, of a sewing-machine embodying my invention. Fig. 2 is a 25 bottom view of the same. Fig. 3 is a sectional view on line 3-3, Fig. 1, looking in the direction of the arrows adjacent to said line. Figs. 4 and 5 are detail views.

A denotes the work-plate, and B the bracket-arm, of a sewing-machine. Journaled in the upper part of the bracket-arm B is the main driving-shaft C, provided with a crank or eccentric c, to which is connected the upper end 30 of a pitman-lever D, the latter being slotted to receive a pivot-pin d, which is rigidly secured in the vertical portion of the bracket-arm. Surrounding the pivot-pin d and embraced by the slotted portion of the pitman-lever is a rocking block E, provided with a 35 curved rocker e, which is rigidly attached to said block or formed integral therewith. The said rocker is slotted to receive a sliding block f, provided with a pin f', to which is jointed the upper end of a link or pitman F, connected at its lower end to an arm g, formed on the rear end of a feed-operating rock-shaft G, suitably journaled beneath the work-plate

of the machine and having at its forward end arms g', in which is pivoted a rod h', to which latter is attached the feed-bar H, provided 55 with a feed-dog h of any well-known construction. Surrounding the rod h' is a torsional spiral spring i, connected at one end to one of the arms g' and at its other end to a pin h³, fixed to the feed-bar H. 60

Pivoted to the vertical part of the bracket-arm B is a feed-regulating bell-crank lever J, the upper arm of which is slotted to embrace the pin f' of the slide or block f, which is movable in the slot of the curved rocker e, so 65 that the said slide or block f may be adjusted nearer to or farther from the pin d, which forms its center of movement, to thereby regulate the rocking movements of the shaft G, and consequently vary the horizontal movements of the feed-bar. When the slide or block f is in the horizontal position shown in 70 Fig. 3, near one outer extremity of the rocker e, the feed movements of the feed-bar will be nearly or quite at their greatest length and in 75 a forward direction; but if the said slide be adjusted to the opposite side of the fulcrum-pin d the feed will be reversed and the length of the reversed feed can of course be varied by adjusting the slide or block f to different 80 positions nearer to or farther from the said fulcrum-pin.

Instead of connecting the lower end of the pitman-lever D directly to the arm of a shaft arranged beneath the work-plate in the usual 85 manner, so as to impart a rotary movement to the said shaft, I have herein shown the said pitman-lever as being somewhat shortened and having its lower end connected by a link or pitman i' to an arm i² on the rear end of a 90 shaft I, supported beneath the work-plate, and to which a rocking instead of a rotating movement is to be imparted. This rocking shaft is herein shown as being provided with an inclined crank-arm i³, provided with a 95 crank-pin i⁴ at a right angle thereto and embraced by a yoke on the rear end of the shuttle-operating lever J, as shown in my application Serial No. 423,143, filed February 29, 1892, and this shuttle-operating mechanism is therefore 100 not claimed in this specification. The said shaft I is provided near its forward end with a cam i⁵, on which rests a pin or roller-stud h³, carried by the feed-bar H, the said

pin or roller-stud being held in contact with the said cam by the torsional spring *i*, connected to the said feed-bar.

- From the foregoing it will be apparent that 5 when the driving-shaft *C* is set in motion a rocking movement will be imparted to the feed-shaft *G* through the pitman-lever and link connection hereinbefore described, and thus longitudinal feeding movement of any 10 desired length may be imparted to the feed-bar, the latter being raised and lowered by the cam on the rock-shaft *I* and the spring co-operating therewith, as will readily be understood.
- 15 It will of course be apparent that instead of the cam on the rock-shaft *I* for raising the feed-bar an equivalent cam for effecting this operation and carried by a rotating shaft may be employed.
- 20 Having thus described my invention, I claim and desire to secure by Letters Patent—
1. In a sewing-machine, the combination, with the main rotating driving-shaft arranged in the upper part of the arm of the machine 25 and provided with a crank or eccentric, of a feed-operating rock-shaft arranged beneath the work-plate of the machine, a feed-bar connected to the forward end of the rock-shaft and provided with a suitable feed-dog, a pit- 30 man-lever operated by said crank or eccentric and provided with a slotted portion, a rocking block embraced by the slotted portion of the said pitman-lever and provided with a slotted rocker, a slide or block arranged 35 in the slot of said rocker and provided with a pin, a link or pitman connecting the said pin with an arm on the rear end of the said feed-operating rock-shaft, a feed-regulating

device for adjusting said block or slide in the said rocker, and means for imparting vertical movements to the said feed-bar.

2. In a sewing-machine, the combination, with the main rotating driving-shaft *C*, journaled in the upper part of the arm of the machine and provided with a crank or eccentric 45 *c*, a feed-operating rock-shaft *G*, arranged beneath the work-plate of the machine and having arms at its forward and rear ends, a feed-bar connected with the arm or arms at the forward end of the said rock-shaft and provided with a suitable feed-dog, a pitman-lever connected to said crank or eccentric and provided with a slotted portion, a rocking block 50 *E*, embraced by the slotted portion of the said pitman-lever and provided with a slotted 55 rocker, an adjustable slide received in the slot of said rocker and provided with a pin, a link or pitman jointed to said pin and to the arm on the rear end of said feed-operating rock-shaft, a feed-regulating lever for adjusting said slide in the slot of the rocker, a shuttle-operating rock-shaft arranged beneath the work-plate of the machine and provided 60 near its forward end with a feed-bar-lifting cam and at its rear end with a suitable arm, 65 a link or pitman connecting the lower end of the said pitman-lever to the said arm on the rear end of the said shuttle-operating rock-shaft, and a spring for assisting in the downward movements of the feed-bar.

In testimony whereof I affix my signature in presence of two witnesses.

JAMES BOLTON.
